UNITED STATES PATENT OFFICE

JOHN H. STONE, OF CHAPEL HILL, TEXAS.

IMPROVEMENT IN FENCES.

Specification forming part of Letters Patent No. 124,516, dated March 12, 1872.

Specification describing a new and Improved Fence, invented by JOHN H. STONE, of Chapel Hill, in the county of Washington and State of Texas.

Figure 1 represents a front elevation of my improved fence. Fig. 2 is a horizontal section of the same on the line *c c*, Fig. 1. Fig. 3 is a vertical transverse section of the same on the line *k k*, Fig. 2.

Similar letters of reference indicate corresponding parts.

This invention relates to a new fence of very simple construction and great strength and durability; and consists in the new arrangement of posts, rails, and false posts, as hereinafter more fully described.

A A in the drawing represent a series of posts, secured in the ground at a depth of from eighteen to twenty-four inches, and at distances apart about twelve inches shorter than the rails to be used. B B are the rails, placed obliquely against the fronts and backs of the posts, and so that the ends of the rails between one pair of posts rest on the ends of the rails between the adjoining pairs, as indicated in Figs. 1 and

2. After the rails have been placed—say, to about half the height of the posts—false posts C C are, by means of wire bands *a*, tied to the posts A against that face of each with which the rails are in contact. The false posts reach from the ground to the height to which the rails are to extend, and serve to confine the latter in their positions. After the false posts have been secured, the remaining rails are applied. The height of the fence may be cheaply increased without the use of rails by having one or more strands, *b*, of wire stretched between or through the posts A. Such wire *b* may, however, be dispensed with.

Having thus described my invention, I claim as new and desire to secure by Letters Patent—

The fence composed of the posts A, oblique rails B, band *a*, and false posts C, substantially as herein shown and described.

JOHN H. STONE.
